FOREIGN PATENT DOCUMENTS

EM 000887583-0002 * 7/2009

Primary Examiner — Dana L Meyrow*(74) Attorney, Agent, or Firm* — Shumaker, Loop & Kendrick, LLP(57) **CLAIM**

The ornamental design for a bottle, as shown and described.

DESCRIPTION

FIG. 1 is a top perspective view of a bottle showing our new design;

FIG. 2 is a front view of the bottle of FIG. 1, wherein the back, left side and right side of the bottle are identical to the front with the exception of the unclaimed spout;

FIG. 3 is a top view of the bottle of FIG. 1; and,

FIG. 4 is a bottom view of the bottle of FIG. 1.
The broken lines in the drawings illustrate portions of the bottle that form no part of the claimed design.**1 Claim, 3 Drawing Sheets**(56)
